DESIGN FOR AN ELECTRIC RAZOR DEMONSTRATING UNIT

George T. Scharfenberg, Chicago, Ill., assignor to
Chicago Flexible Shaft Company, Chicago, Ill.,
a corporation of Illinois

Application August 19, 1940, Serial No. 94,496

Term of patent 7 years

To all whom it may concern:

Be it known that I, George T. Scharfenberg, a citizen of the United States, residing at Chicago, in the county of Cook and State of Illinois, have invented a new, original, and ornamental Design for an Electric Razor Demonstrating Unit, of which the following is a specification, reference being had to the accompanying drawings, forming part thereof.

In the drawings:

Fig. 1 is a perspective view of an electric razor

demonstrating unit embodying my new design;
and

Figs. 2 and 3 are top and side views, respectively, thereof.

The dominant features of the design reside in the portions shown in full lines.

I claim:

The ornamental design for an electric razor demonstrating unit, substantially as shown and described.

GEORGE T. SCHARFENBERG.
